UNITED STATES PATENT OFFICE.

NORMAN JOSEPH LOCKYER, OF LENZIE, SCOTLAND.

HYDRAULIC AIR-COMPRESSOR.

SPECIFICATION forming part of Letters Patent No. 645,109, dated March 13, 1900.

Application filed November 3, 1896. Serial No. 610,972. (No model.)

To all whom it may concern:

Be it known that I, NORMAN JOSEPH LOCKYER, engineer, of 14 Regent Square, Lenzie, in the county of Dumbarton, Scotland, have 5 invented certain new and useful Improvements in Air-Compressing Apparatus for Raising Beer or other Liquids, of which the following is a specification.

This invention relates to apparatus for compressing air for use in raising liquids, such as beer, from barrels in cellars for delivery at the counter, the improved apparatus being operated by water under regulated pressure from the town's supply or other source and the desired air-pressure being maintained notwithstanding variable consumption.

The invention is illustrated by the accompanying drawings.

Figure 1 is a vertical section of the apparatus, and Fig. 2 a modification of a detail.

The improved apparatus comprises a cylindrical or other vessel A, to which water is admitted from the main for the purpose of compressing air within the vessel and from 25 which it is exhausted to admit a fresh-air supply before repeating the compressing operation. The water is admitted through a pressure-regulating valve B, hereinafter referred to, and thence through an inlet C in 30 the lower end of the air vessel or casing A, a waste-water outlet D being fitted in proximity to the inlet and both terminating in a valve-casing E, in which is fitted a piston-valve F, adapted to cover or close the outlet D as the inlet C is opened and, vice versa, to close the inlet C as the outlet D is opened. The operation of this valve F is effected automatically by means of a tumbler-lever G, which in turn is actuated by a float H, rising 35 with the inflowing water and descending on the discharge of the waste water, the inlet C being opened on the descent of the float H to its lowest point, as shown by the drawings, and the discharge-outlet D being opened when the float H has by the filling of the casing A been raised to its highest level, as indicated by the dotted lines. The valve F being opened, water under pressure enters and gradually fills the casing A, the air within it 45 being compressed and forced through a non-return valve I, fitted at the top, whence it passes through a flood-preventer, hereinafter

described, to a pressure-chamber or directly to the barrels from which the beer is to be raised. As the water enters the casing A the 55 float H rises with it, being guided in its movement by a slotted tube J, extending vertically upward from the bottom of the casing A. On reaching nearly to its highest point the float comes into contact with a cross piece or 60 disk K on the upper end of a rod L inside the slotted tube J, said rod L having attached to its lower end a slotted bar M, which can freely rise and fall inside the vertical tube J. The slotted bar M engages one arm of a bell-crank N, whose other arm is connected by means of slotted links O to the piston-valve F, which controls the admission and discharge of the water. The third arm G on bell-crank spindle P is fitted with a weight 65 G' and acts as a tumbler to operate the valve quickly. When the annular float H comes in contact with the cross piece or disk K on the vertical rod L, it continues to ascend with the water, and the slotted bar M at its lower 70 end rises with it and tilts the bell-crank N until the arm G, carrying the weight G', passes the vertical position, when the tumbler falls over by gravity. A pin N' in the end of the second arm of the bell-crank N is 75 by this movement caused to traverse the slot in the links O, connected to the piston-valve F, and push over the valve, so as to close the inlet-port C and shut off the supply of water under pressure, at the same time opening the 80 discharge-port D, through which the water in the casing A runs out. When the discharge-port D is opened, an annular passage F', formed around the piston-valve F, brings a passage F², leading from the outside of the 85 casing A, into communication with an air-tube P, and thus permits a fresh supply of air to enter the casing A, or the partial vacuum caused by the discharge of the water may open an air-valve Q in a pipe P', secured on 90 the casing, as shown at Fig. 2, to admit a fresh supply of air. As the water-level falls the float H descends until it rests on projections R on the slotted bar M, and as the water-level continues to fall the weight of the 95 float H, resting on the projections R, increases until it becomes sufficient to overcome the resistance of the weighted tumbler-arm G. The bell-crank N then falls back 100

into the original position and moves the piston-valve F with it, thus allowing a fresh supply of water under pressure to enter the casing A through the inlet-port C.

5 For the purpose of regulating the pressure of the water entering the air-compressor A, and thus regulating the pressure of the air delivered, the automatic pressure reducing or regulating valve B is provided on the inlet-pipe T from the main. This is composed of a casing U, having a piston-valve U', closing on the annular inlet-orifice and attached to a metallic, leather, or other diaphragm U², held down by a spring, the pressure on which 10 is regulated by screw-nuts or by a weighted lever U³, as shown. From the chamber formed under the diaphragm the water enters the air-compressor by the inlet-port C. Whenever the pressure on the under side of 15 the diaphragm U² exceeds a given amount, the spring is compressed or the lever U³ lifted, and the valve reduces or closes the water-supply until the pressure in the air-compressor A, and consequently that under the 20 diaphragm U², is reduced by the reduction of air-pressure in the casks, owing to beer being consumed or to leakage.

In the event of failure of the mechanism in the air-compressor A it is necessary to prevent 25 the entrance of water under pressure into the air-pipe V, and thus into the casks. For this purpose I provide a combined non-return-valve chamber and a flood-preventing device. This is composed of a closed casing 30 W, connected to the upper end of the compression vessel A by an orifice fitted with the self-closing non-return valve I, already mentioned, and having in it a float W², having on its upper side a valve W³, adapted to close 35 against a seat W⁴, formed on the outlet for the compressed air, the float W² being conveniently guided by an extension of the valve-spindle W⁵ into the air-delivery pipe V. So long as air is being delivered by the 40 compressor A the valve W³ on the float W² re-

mains off its seat W⁴ and the float W² does not move. When water, however, passes the non-return valve I, the float W² rises and the valve W³ on it takes its seat W⁴, closing the air-delivery pipe V to the casks. This apparatus is designedly somewhat difficult to restart after a failure of the air-compressor A, so as to render necessary an examination of the parts. The non-return valve I cannot rise from its seat sufficiently to permit of the float 55 W² being raised by the air-pressure, and thus prevent the valve W³ upon the float from stopping the delivery of air to the casks.

Having now described the invention, what I desire to claim and secure by Letters Patent 60 is—

1. In an apparatus for compressing air having suitable air inlet and outlet, and also suitable water inlet and outlet, a piston-valve controlling both water-openings and the air-inlet, 65 a tumbler-lever connected with said valve, and a float adapted, when it arrives near the upper end of its course, to operate said lever and thus cause the valve to close the water-inlet and open the air-inlet and water-outlet, 70 and when said float arrives near the lower end of its course, to open the water-inlet and close the air-inlet and water-outlet, substantially as set forth.

2. In apparatus for compressing air, the 75 combination with an air-chamber having suitable water and air inlet and outlet pipes, of a valve controlling the water inlet and outlet, a float, a slotted tube J along which the same moves, rod L moving in said tube and adapted 80 to engage with the float and having a slotted portion M, and bell-crank lever N actuated by said slotted portion and adapted to operate aforesaid valve, substantially as set forth.

Signed at Glasgow, in the county of Lanark, 85 Scotland, this 20th day of October, 1896.

NORMAN JOSEPH LOCKYER.
